UNITED STATES PATENT OFFICE.

ERRETT E. PHILLIPS, OF NEW CASTLE, PENNSYLVANIA.

EXCAVATING APPARATUS.

1,356,008.

Specification of Letters Patent.

Patented Oct. 19, 1920.

Application filed August 9, 1919. Serial No. 316,383.

To all whom it may concern:

Be it known that I, ERRETT E. PHILLIPS, a citizen of the United States, residing at New Castle, in the county of Lawrence and State of Pennsylvania, have invented certain new and useful Improvements in Excavating Apparatus; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in hoisting and excavating apparatus for use upon the surface of the ground or underneath same for various purposes, where soil and various materials are desired to be excavated, hoisted and dumped.

My invention consists of a simple and efficient device of this character having various details of constructions, combination and arrangement of parts which will be hereinafter fully described, shown in the accompanying drawings and then specifically defined in the appended claims.

My invention is illustrated in the accompanying drawings which, with the letters of reference marked thereon, form a part of this application, and in which:

Figure 1 is a side elevation showing the application of my invention to a derrick, having a swinging boom, with scoop shovel mounted thereon.

Fig. 2 is a cross sectional view through the form illustrated in Fig. 1, showing in top plan view parts of the invention.

Fig. 2^a is a detail perspective view of means for holding the boom in adjusted position.

Fig. 3 is an enlarged detail view partly in section illustrating means for holding the reel from rotation independent of the capstan shaft upon which it is mounted.

Fig. 4 is a detail sectional view longitudinally through the scoop shovel showing parts in elevation.

Fig. 5 is a view in elevation showing the application of my invention to a shaft and cage.

Fig. 6 is a detail perspective view of a reel, and means for raising and lowering a cable while being wound upon the reel.

Fig. 6^a is a detail view of the locking means for the elevator.

Fig. 7 is an enlarged detail perspective view of the means for raising the cable, 60 and

Fig. 8 is a detail view of means for holding the boom, illustrated in Fig. 1, in different adjusted positions.

Reference now being had to the details 65 of the drawings by numerals:

Referring to Fig. 1 of the drawings, 1 designates the base upon which a suitable derrick 2 is mounted, having cross beams 3 at the upper end thereof, in which are 70 journaled pulleys 4 and 5. A pulley 6 is journaled in suitable bearings upon a cross piece 7 of the derrick, and 8 designates another pulley which is journaled in suitable bearings near the lower part of the derrick. 75

A swinging boom, having parallel pieces, has a bracket shaped member 9' connecting their inner ends, and which member is pivotally connected at 10 to a yoke 11, having apertures to receive the vertically disposed 80 rod 12 which is fixed to the derrick spaced apart a slight distance therefrom, as shown clearly in Fig. 1 of the drawings. A cable 13 is secured to the scoop shovel 17 and passes over the pulleys 4, 4' and 5 underneath the pulleys 8 and thence extends to and passes about a reel 26 journaled upon the capstan shaft 27', which has a squared end 27 adapted to receive the capstan lever 31 provided with a similarly outlined opening therein to receive the angular outlined part of the capstan shaft 27'. Integral lugs 28 project from the upper face of the reel, and are provided with registering apertures to receive the rod 30 as shown clearly in Fig. 90 95 3 of the drawings, which rod also passes through a registering aperture in the capstan. A rope 14' is fastened at 14 to the yoke 11 and passes over the pulley 6, and carries at its other end a handle piece 14^a, 100 which affords means for raising and lowering the boom.

A bracket member 13' has angled portions parallel with each other and apertured to receive the rod 12, the ends of said bracket 105 member and the yoke 11 being in contact with each other, as shown clearly in Fig. 2^a of the drawings. Said bracket member has laterally extending rods 13^x designed to swing into the spaces intermediate the two 110 lugs 1 upon the frame, when it is desired to hold the boom in an adjusted position.

A handle 1^A is fastened to the bracket member and serves as a means for swinging the latter to engage the spaces intermediate the lugs or to be drawn free from the same 5 to permit the boom to be raised and lowered while in operation.

In Fig. 8 of the drawings is shown additional means for holding the boom in different adjusted positions, and consisting of 10 yokes 35 having integral collars 36 at the ends thereof, adapted to receive the vertical rod 12 rising from the sill of the derrick, and which yoke has a handle 37 fixed thereto, providing a convenient means for swinging 15 the yoke, so that the projecting members 38 thereof may be made to engage the recesses 39 in the post 40 of the derrick.

A scoop shovel, Fig. 4, 17, with a suitable handle 17', has straps 18 fastened thereto, 20 each of which is supported by rings 19, adapted to receive the rod 16 upon which they are movable. Said scoop shovel has a rear end 20 which is hinged at 21, and is provided with a latch 22, and 23 is a rope 25 fastened to said latch and forms means for releasing the same when it is desired to dump below it.

In Fig. 5, I have shown my invention illustrating a vertical hoisting cage 40, which has guide wheels 41 bearing against 30 vertically disposed parallel tracks 42, said Fig. 5 illustrating a car 43 mounted upon wheels, this car is within the cage 40. A hoisting cable 44 is secured to ring bolt 45 upon the cage, passes over a pulley 46 rotating on top of the shaft 47, which latter also carries a pulley 48. Said cable 44 passes underneath a pulley 49, and thence extends to 35 and passes about a winding reel 50, which is of similar construction to the reel before described, and illustrated in detail in Fig. 3 of the drawings, said reel having, however, a slightly modified form of means for causing the reel and capstan to rotate together, 40 which consists of a sliding angle rod 51 held in suitable eyes 52, and adapted to engage apertures 53 upon the reel, said eyes 52 projecting from the lever 54.

Upon reference to Fig. 6 of the drawings, 50 it will be noted that the rope 44 passes over a roller 55 which has a vertical movement, detail of which is shown in Fig. 7 of the drawings. Said roller 55 is mounted upon a bar 56, and 57 is a lever fulcrumed upon a 55 pin 58 upon the standard 59 and which is connected to the bar, and by pressure on the lever, the bar carrying the roller may be raised to the position shown in dotted lines in Fig. 7 of the drawings. As a means for holding the bar carrying the roller in different adjusted positions, a bracket rod 60 is shown as having angled ends adapted to engage apertures in the standards 61. The capstan shaft, it will be noted upon reference to Fig. 5 of the drawings, is supported

70 by bars, these laid in concrete for foundation. For purpose of guarding the entrance to the elevator shaft at the surface of the ground, a suitable screen 42' is placed upon the shaft.

A suitable counter balance weight 62, 75 shown in Fig. 5, has a rope 63 fastened thereto which passes over pulleys 64, and thence about the pulleys 48, in order to hold the cage in elevated positions. Ring bolts, 75 one designated by numeral 65 and fastened to a cross beam 66 of the shaft in which the cage is mounted, and the other, 67, on the cage, and 68 designates a double ended snap hook designed to engage the two ring bolts 80 when the cage is elevated.

In the modified form of means for holding the cage elevated, consisting of a chain 79 passing through rings, as shown in Fig. 5 of the drawings, and a padlock 71 may be 85 passed through the rings at the end of the chain to hold same locked. An additional means for supporting the cage consists of a horizontally movable rack bar 72 having teeth upon the under surface thereof, and 90 designed to be engaged by the teeth of the gear wheels 73, one of said wheels being rotated by means of a crank handle secured thereto, so that when the cage is elevated, the rack bar may be moved underneath the 95 same by rotating one of the gear wheels.

In operation, through the medium of the hoisting cable 13, the boom 9 may be held to operate at different elevations. By rotating the capstan 11 the reel will cause the 100 cable 13 to wind thereon and the scoop shovel may be drawn through the soil or other material, the scoop shovel being directed through the medium of the handle 17', and when the scoop shovel is loaded and 105 further pulling applied to the hoisting cable 13, the boom 9 may be elevated to any desired position and may be swung in different directions laterally, and when it is desired to dump the load, it may be done by the 110 operator pulling upon the rope releasing the latch upon the scoop shovel, permitting the material to fall out at the rear end thereof.

When it is desired to pull back the scoop 115 shovel to its original starting position, the rod 30 may be withdrawn from engagement with registering apertures in the lugs upon the reel and capstan, and the scoop shovel may be pulled back through the medium of 120 the rope 23 secured thereto. The boom, it will be noted, may be held in different positions through the various means illustrated in Fig. 2^A of the drawings, or through the medium of the mechanism shown in Fig. 8. 125 The cable, as it winds upon the reel, may be raised through the medium of the lever 57 in order to permit the cable to wind evenly upon the reel. It will be noted that the means for causing the reel and the capstan 130

to wind together is of similar construction, shown in Figs. 1 and 5 of the drawings, the cage in Fig. 5 being permitted to be lowered by releasing the angled rod connecting the reel to the capstan.

By the provision of a hoisting apparatus made in accordance with my invention, it will be noted that a simple and efficient mechanism is provided for use either upon the surface of the ground or underneath as may be desired, and while I have shown a particular detailed construction of applying the principle involved in my invention, it will be understood that the detailed construction may be varied in different ways without in any way departing from the spirit of the invention.

What I claim to be new is:

1. An apparatus for hoisting booms, comprising a derrick, a vertical guide rod carried by and spaced slightly from the derrick, a yoke provided with apertures through which said guide rod passes, a swinging boom pivoted to said yoke, a bracket member having parallel angled portions apertured to receive said guide rod, the ends of said yoke and said angled portions being superposed, laterally extending arms carried by said bracket member, and a series of spaced lugs carried by said derrick between pairs of which said arms are adapted to be moved to hold said boom in vertically adjusted position on said guide rod.

rick between pairs of which said arms are adapted to be moved to hold said boom in vertically adjusted position on said guide rod.

2. An apparatus for hoisting booms, comprising a derrick, a vertical guide rod carried by and spaced slightly from the derrick, a yoke provided with apertures through which said guide rod passes, a swinging boom pivoted to said yoke, a bracket member having parallel angled portions apertured to receive said guide rod, the ends of said yoke and said angled portions being superposed, laterally extending arms carried by said bracket member, a series of spaced lugs carried by said derrick between pairs of which said arms are adapted to be moved to hold said boom in vertically adjusted position on said guide rod, and a handle carried by said bracket member by which the latter may be horizontally swung so as to cause said arms to move between pairs of said lugs.

In testimony whereof I hereunto affix my signature in presence of two witnesses.

ERRETT E. PHILLIPS.
